COMBINED BELT BUCKLE AND HOLDER FOR A LIGHTER OR SIMILAR ARTICLE

Wilfred W. Weingardt, 5247 Southeastern Ave.,
Indianapolis, Ind. 46201

Filed Apr. 1, 1969, Ser. No. 16,529

Term of patent 14 years

Int. Cl. D2—08

U.S. Cl. D2—406

Fig. 1

Fig. 2

Fig. 4

Fig. 3

FIG. 1 is a front view of a combined belt buckle and holder for a lighter or similar article showing my new design;

FIG. 2 is a top plan view thereof;

FIG. 3 is an end view thereof; and

FIG. 4 is a rear view thereof.

I claim:

The ornamental design for a combined belt buckle and holder for a lighter or similar article, as shown.
